UNITED STATES PATENT OFFICE.

EDWARD J. YETTER, OF DENVER, COLORADO.

ROOFING-CLEAT.

Specification of Letters Patent. Patented Aug. 3, 1915.

1,148,647.

Application filed August 4, 1914. Serial No. 855,042.

To all whom it may concern:

Be it known that I, EDWARD J. YETTER, a citizen of the United States of America, residing at the city and county of Denver and State of Colorado, have invented a new and useful Roofing-Cleat, of which the following is a specification.

My invention is for a new double joint lap binding and clamping cleat for securing roofing sheets to the roofs and sides of buildings; and the objects of my invention are: First, to provide a double joint lap binding and clamping cleat that will shed water from the upper sheet of a roof, and that will prevent water backing up on the lower sheet into and through the lap joint between the sheets. And second, to provide a double joint lap binding and clamping cleat, that covers the edge of the lap joint between the sheets, and that is of such a trussed form of cross section that when secured in position by nails on a roof of a building, that the edges of its flanges embed themselves in the lapped sheeting. I attain these objects by the mechanism illustrated in the accompanying drawings, in which:

Figure 1, is a perspective view, illustrating portions of two sheets of roofing material, the overlapping edges of which are secured by the improved clamping cleat, said cleat being provided with raised nail-receiving caps. Fig. 2, is a view similar to Fig. 1, but showing the cleat provided with depressed or counter-sunk nail receiving caps. Fig. 3, is an enlarged vertical sectional view on the line 3—3 of Fig. 1. Fig. 4, is a similar sectional view on the line 4—4 of Fig. 2. Fig. 5, is an enlarged perspective view of a portion of a cleat of the style shown in Figs. 1 and 3. Fig. 6, is a perspective view of a cleat in which the nail receiving caps are omitted. Fig. 7, is a perspective view of the end portion of a cleat, the metal being pressed so as to close the end of the cleat. And Figs. 8 and 9, are views illustrating the manner of securing roofing sheets to the roofs and sidings of buildings, the sheets being shown at right angles to the pitch of the roof and in the same direction as the pitch of the roof.

Similar letters of reference refer to similar parts throughout the several views.

Referring to the drawings, the numeral 1 designates a cleat embodying my invention. This cleat may be made of metal, wood or of any other suitable material.

My invention, however, contemplates a cleat that is designed to be placed over the side edge of the top layer of the roofing sheeting, and that rests against the lower layer, as well as against the top layer of the sheeting. This arrangement requires a novel and special form and arrangement of cleat, and I have especially invented and designed it in such a manner as that its opposite side edges are clampingly indented in the sheetings of both layers of the sheeting, and the side edge of the cleat that rests on the lower or bottom sheathing by virtue of its indentation into the bottom sheeting when nailed tightly to the roof boards prevents water from backing up into and through the overlapping joint between the two layers of sheeting.

My improved double joint making cleat comprises narrow strips of metal or other suitable material, but preferably made of galvanized iron, that comprise a central body portion 2, which is preferably made flat, and on each of the opposite sides of the central body portion bevel flanges 3 and 4 are formed, the edges of which form the sheeting indenting and clamping edges of the cleat. These flanges, however, are made of different angles, the angle 3 being the flatter, and it forms a downward sloping angle from the central body portion of the cleat, that is of sufficient bevel to allow its edge to embed itself into the upper sheet, and also to allow water to run readily up over it and the cleat from the upper sheet. The flange 4 is made to extend at a sharper downward angle to the central body portion of the clamp than the flange 3, in order that its edge may extend down over the edge of the upper sheet, and rest firmly against and embed itself into the surface of the lower sheet of the roof sheeting, and the edges of the flanges when the cleat is made of galvanized iron of about a thirty-second of an inch in thickness, are sharp enough to be embedded into the roofing sheets when nailed on the sheeting on a roof by roofing nails, which is the means employed to secure them to the overlapping joints of the sheeting sheets. To prevent the edges sinking into the sheets too far when very thin galvanized iron is used, the edges may, if desired, be slightly turned or rolled to one side or flattened, as shown in Fig. 5.

I preferably provide my improved cleats with nail receiving holes, which are punched

into the cleats at such distances apart as is necessary to firmly secure the cleats to the roofing sheet, and at the same time clamp the overlapping joints of the sheets 5 tightly together. I have found in practice that the cleats should be nailed to the sheets and roof about every three inches of their length, and I preferably provide them with nail receiving holes placed at that distance 10 apart. Inasmuch, however, as my improved cleat covers the edge of the top sheet at its lapping joint, I preferably position these nail receiving holes out of the center of the width of the cleat, and nearer to the upper 15 flange 3 of the cleat than to its lower flange 4.

The central body portion of my improved cleat where the nail receiving holes are formed, may be made flat if desired, and the 20 cleat made of a thickness of metal that will permit the nails to be driven against the cleats without tending to flatten and spread out or apart the side flanges of the cleat opposite to the nail receiving holes. I preferably reinforcingly truss the cleats around the nail receiving holes, in order to strengthen the cleats at these points, and while there are a number of ways in which this feature of my invention may be carried out, I preferably arrange it in the 30 following manner: Around each nail receiving hole at the time the holes are punched through the cleats, I form a cap portion 6. This cap portion may be a depressed 35 cap portion, as shown in Figs. 2 and 4, or a raised cap portion as shown in Figs. 1 and 3, which is the preferred construction when these cap portions are used. This cap portion comprises a circular button-like portion, that is pressed to project 40 from the metal. This cap is preferably placed centrally in the width of the central portion of the cleat, as shown in Fig. 3, and the nail hole is punched through the center 45 of the cap. The opposite ends of the cleat strips may be of any desired shape, such as square, and the side flanges are of the same form as the cross section of the cleat, or the ends may be rounded, or they may 50 be turned down to close the opposite ends of the strips.

The application of my improved cleat to sheets of roof sheeting and its operation in securing their overlapping edges together 55 and to the boards of the roof or side of a building to form water-tight joints between the sheets, is as follows: Each sheet is laid to overlap the one below it, by from about an inch and a half to two inches, and the 60 cleats are laid over the overlapping joint

with their flange 4 substantially up against the edge of the upper sheet, and the cleats may be made in lengths of from several inches to several feet, most of them being made in such lengths as the sheet metal or material can be obtained of the longest lengths in, but cleats made in different lengths are an advantage in finishing out the ends of a sheet at the ends or sides of roofs of buildings, and they are laid end to end along the overlapping joints of the roofing sheets across the roofs or sides of buildings, and are firmly and solidly nailed to the sheets, the heads of the nails being driven down tight against the cleat to force the edges of its flanges to slightly embed themselves into the surfaces of the roofing sheets, which acts to make a double joint on the sheet, one joint being made by the edge of the flange 3 embedding itself into the surface of the top sheet, and the other joint being formed by the edge of the flange 4 embedding itself into the surface of the lower sheet, while the entire pressure of the central portion of the cleat is forced down 85 against the edge portion of the top sheet, and it is pressed and clamped down against the lower sheet with a pressure that acts to securely bind the overlapping edges of the sheets together tight enough to form a 90 water-proof joint between the sheets and at the same time the nails firmly secure them to the roof or side boards of the building.

My invention provides a strong rigid lap covering cleat that will bind and clamp 95 both the lower and upper sheets against the building, and also bind them together and secure them to the building.

Having described my invention, what I claim as new and desire to secure by Letters Patent, is:

A cleat for lap-joints of sheet-roofing, comprising a metal strip having its edges bent downward to form two longitudinal flanges, one of said flanges being bent at an abrupt angle, whereby it may extend close to the lower edge of the upper sheet, and of such width that its edge may engage the surface of the lower sheet, the other flange being bent at a less angle, whereby its edge 110 may engage the surface of the upper sheet, said strip having perforations therein so arranged that nails driven therethrough will pass through both sheets.

In testimony whereof I affix my signature 115 in presence of two witnesses.

EDWARD J. YETTER.
